UNITED STATES PATENT OFFICE.

MICHAEL W. GILMARTIN, OF LAKE DENMARK, NEW JERSEY, ASSIGNOR TO THE YALE & TOWNE MANUFACTURING COMPANY, OF STAMFORD, CONNECTICUT.

GRAPPLER.

1,039,727.

Specification of Letters Patent.

Patented Oct. 1, 1912.

Application filed July 18, 1911. Serial No. 639,917.

To all whom it may concern:

Be it known that I, MICHAEL W. GILMARTIN, of Lake Denmark, in the county of Morris and State of New Jersey, have invented certain new and useful Improvements in Grapples; and I do hereby declare the following to be a full, clear, and exact description of the invention, such as will enable others skilled in the art to which it appertains to make and use the same.

My invention relates to an improved grapple for handling and transporting cylindrical bodies such as projectiles, pipes, shafts, rolls of paper, barrels etc., and it consists of a yoke of substantially inverted U-shape, adapted to straddle the article to be lifted or handled, and provided with one or more latches so located that when the yoke is dropped over the body to be lifted, the latch or latches will engage the article below its greatest diameter, and lock the article within the yoke.

In the accompanying drawings, Figure 1 is a view in side elevation showing my improved device locked to a cylindrical object. Fig. 2 is a view in section of the same showing the latches open to release the yoke from the object. Fig. 3 is a view in side elevation and Figs. 4, 5, 6, 7, 8, 9 and 10 are views of modifications.

1 represents the yoke, the upper portion of which is preferably semi-cylindrical in shape with the lower free ends 2 flared outwardly so as to permit an article of a given size to readily enter the yoke, or rather permit the yoke to pass onto and embrace the article.

In the drawings, I have shown a projectile in connection with the yoke, but it is evident that the device is equally well adapted for handling and transporting cylindrical bodies of any kind, such as pipes, shafts, rolls of paper, barrels, etc., hence reference herein to projectiles is intended to cover and include cylindrical articles of any kind or articles of other shapes that conform in size to the yoke and come within the limits necessary for the proper action of the locking latches.

The locking latches 3 are pivotally mounted in the bifurcated and outwardly flaring ends 2 of the yoke 1, on bolts or pins 4, and are cam shaped, so that when in their normal position, their inner or bearing faces will project inwardly sufficiently

to prevent the release of an article embraced by the yoke. These latches shown in Figs. 1 to 6 inclusive normally rest and fall into closed position by gravity, and are retained within the zone of gravity influence by the set screws 5, which latter are mounted in the sides of the yoke with their free ends resting within slots 6 in the latches 3. These slots and set screws limit the outward or opening movement of the latches, and always maintain the preponderance of weight of the latches in planes intermediate the vertical center of the pivot bolts 4 so that, it matters not to what extent the latches may be moved in placing the yoke on the projectile, they will fall into locking position, the instant they pass below the greatest diameter of the projectile. In order to take the whole or a portion of the weight of the projectile off the set screws 5 which are primarily designed to limit the opening movement of the latches, I provide each end of the yoke with a shoulder 7 against which the free ends 8 of the latches rest when the latches are closed as in Fig. 1. By means of the shoulder 7 and screw 5, the latches are prevented from passing either up or down, beyond the effective point of action, hence are always in condition to permit the yoke to be passed onto a projectile, and then fall and lock the yoke to the projectile.

As shown, the yoke 1 is provided at its upper end with a ring which may be formed integral with the yoke, but which I have shown separate and secured thereto by a nut. This ring is for the attachment of a hoisting hook or other means for handling and transporting the yoke and its load, and for steadyng the projectile and to prevent it from tilting within the yoke, I have provided the latter at its opposite sides at the top, with the projecting flanges 8a, which latter form rests for the projectile and materially increase the bearing surface of the yoke at the top.

After the projectile has been lifted and transported to the objective point, it is lowered onto a support, thus taking the weight off the latches and leaving the latter free to be moved to unlocking or releasing position. In Figs. 1, 2 and 3, I have shown the latches provided with finger pieces 9 by which they may be moved to open position, and in Fig. 5, I have shown the bolt carrying the latches with a lever 10. In this latter construction,

the latches will be fast to the bolt so that by moving the lever 10 the latch will be shifted. In the construction shown in Fig. 5, and also in Fig. 4, a spring assists gravity in maintaining the latch in its closed position. In the construction shown in Fig. 5, the spring 11 is secured to the bolt 4^a and bears against the pin 12 projecting laterally from the yoke, whereas in the construction shown in Fig. 4, the spring 11^a is mounted on the rod 13 between the head 13^a and the lug 14 on the yoke, through which said rod passes, the lower end of said rod being pivotally secured to the latch. With this latter construction, by simply pressing down on the head 13^a, the latch will be turned to its open position.

In the construction shown in Fig. 6, instead of bifurcating the ends as in the previously described constructions, I provide 20 the yoke with brackets 15, the ends of which rest within slots in the latches, the latter being secured to the brackets by bolts or pins. This permits me to use much longer latches 25 which are desirable when handling soft material, such as paper rolls.

If it be desired to use one latch only, the other can be locked in any position, against movement, by the set screw 16, one for each 30 latch. These set screws are mounted in the yoke, and are adapted to be forced against the side face of the latches and lock the latter against movement.

In the construction shown in Fig. 7, I 35 show locking latches 3 which tend to fall by gravity into locking position, but which are yieldingly held in unlocking position by the flat springs 11^b which are riveted at one end to the yoke, and bear against the latches 40 in a position to hold same up, or in their unlocking positions. In operation, therefore, when the yoke is dropped over an article, the locking latches must be pushed into their locking positions or against the article 45 within the yoke, and then as the yoke is lifted and the weight falls onto the latches, and the latter are held in their locking position by the load. When the yoke is lowered and the weight taken from the latches, 50 the springs then automatically throw the latches to unlocked position, thus leaving the yoke free to be withdrawn.

Fig. 8 shows the locking latches 3^a weighted at their outer ends, so that they normally 55 are in their unlocking position, hence like the construction last above described, must be turned into locking position, and automatically release the article by the removal of the weight from the latches.

60 In the construction illustrated in Fig. 9, the latches are provided each with a movable gravity device, consisting in the present instance of an arm 17^a pivoted at 17^b to the latch, and provided at its opposite end with 65 the weight 17. Each latch is provided with

the pins or stops 18 one on each side of the axis or pivot of the latter, so that the gravity device may be turned so as to add its weight to either end of the latch, hence when turned so as to bear on the pin adjacent the inner end of the latch, the latter will operate to automatically lock, and when turned to bear on the pin adjacent the outer end of the latch the latch will operate to automatically unlock.

75 In Fig. 10, I have shown the yoke provided with adjustable screws 18^a with lock nuts 19 for holding the screws against movement. These screws or posts are designed to be adjusted to accommodate and hold cylinders smaller than the yoke, and while I prefer two, one so located that it and the co-operating latch engage the cylinder below the greatest diameter of the latch, and the other in a plane above so as to properly 80 space the yoke with relation to the cylinder, I may use only the lower one. It is also evident that instead of using screws as shown, precisely the same results may be accomplished by filling blocks or adjustable devices of various kinds.

85 Instead of, or in addition to, the finger pieces 9, I may provide the gravity latches with the opening wires 20, 20, whereby both latches may be conveniently actuated simultaneously. Each wire 20 is passed through a hole 21 in the lower end of a latch and is secured therein, and each latch is grooved as at 22 above the hole 21 as to permit of the necessary inward movement 100 of the latches. The wires pass up over the yoke and preferably through guides 23 secured to the yoke, and are secured to a handle 24, preferably in the form of a ring, embracing the hoist ring of the yoke, and if 105 desired, the handle 24 may be attached to a cord or wire 25 leading up through a pulley on the hoist block. By this arrangement, when the yoke with a projectile therein is lowered into a support, the operator can 110 with one hand, by pulling up on handle 24 throw the latches to unlocking or releasing position and lift the yoke off the projectile. With these devices it will be seen that after the latches pass below the greatest diameter 115 of the projectile and fall or are moved into contact with the projectile, they will positively lock the yoke to the projectile. The yoke with its load may now be raised and transported by crane, traveling block or 120 other means to the objective point, and after it has been lowered onto a support, so as to remove the weight from the latches, the latter can be readily opened by hand or automatically as previously explained thus leaving the yoke free to be removed.

125 It is evident that many slight changes might be resorted to in the relative arrangement of parts shown and described without departing from the spirit and scope of my 130

invention. Hence I would have it understood that I do not wish to confine myself to the exact construction and arrangement of parts shown and described, but

5 Having fully described my invention what I claim as new and desire to secure by Letters-Patent, is:—

1. In a grapple, the combination of a yoke comprising an inverted U-shaped structure 10 of a size and shape to conform to the body to be lifted, a gravity latch mounted in the lower end of an arm of said yoke so as to form a rest and support for said body below its greatest diameter, and rigid stop on the 15 arm carrying the latch for limiting the downward movement of the latch.

2. In a grapple, the combination of a yoke comprising an enlarged rigid structure 20 adapted to straddle the object to be lifted and conforming in shape to the part of said object embraced by the yoke, a latch mounted in the lower end of an arm of said yoke and adapted to engage the object below the greatest diameter of the latter, the said latch 25 free to give or yield to permit the yoke to straddle the object, and a rigid stop on the arm carrying the latch for limiting the downward movement of the latch.

3. In a grapple, the combination of a yoke 30 comprising a rigid structure adapted to embrace the major part of a cylindrical object the lower ends of said yoke being turned outwardly so as to freely permit of the passage of the yoke onto the object, a gravity latch mounted in the lower end of an arm of said yoke and adapted to engage the object below the greatest diameter of the latter and form a seat for the same and a rigid stop on the arm carrying the latch for 35 limiting the downward movement of the latch.

4. In a grapple, the combination of a yoke comprising an integral structure adapted to straddle the object to be lifted and conforming in shape to the part of said object embraced by the yoke, a latch adjacent the lower end of each depending member of the yoke the said latches adapted to open upwardly and when lowered engage the object 45 below its greatest diameter and form seats on which said object rests, and rigid stops for limiting the downward movement of the latches whereby they are supported in positions to sustain the load resting thereon.

5. In a grapple, the combination of a yoke 55 comprising an integral semi-cylindrical yoke adapted to straddle the object to be lifted and conforming in shape to the part of said object embraced by the yoke, the lower ends of said yoke being turned outwardly so as to freely permit of the engagement and disengagement of the yoke and object to be lifted, a latch carried by the lower end of each depending member of the yoke, the said latches adapted to open upwardly and when 60 lowered form seats on which the objects rest and rigid stops for limiting the downward movements of the latches whereby they are supported in position to sustain the load resting thereon.

6. In a grapple, the combination of a yoke comprising an inverted U-shaped rigid structure adapted to straddle a cylindrical object, the two depending members of said yoke projecting below the greatest diameter 75 of said object whereby the widest portion of said object may be embraced by said yoke, a latch pivoted to each depending arm and adapted to project inwardly so as to engage the object below its greatest diameter and 80 means for locking one of said latches in an inoperative position.

7. In a grapple, the combination of a yoke comprising an inverted U-shaped structure 85 for lifting cylindrical objects, the said yoke being of a shape and size to embrace and fit the upper half of the object, a latch mounted in the lower end of a depending member of said yoke so as to engage the object below the greatest diameter of the latter, a spring for holding the latch normally open, and a rigid stop against which the latch rests when supporting a load.

8. In a grapple, the combination of a yoke semi-cylindrical in shape and adapted to 95 straddle a cylindrical object, a latch mounted in the lower free end of one member of said yoke and adapted to form a seat below the greatest diameter of said object on which the object rests, and a flexible device attached to said latch for retracting the same.

In testimony whereof, I have signed this specification in the presence of two subscribing witnesses.

MICHAEL W. GILMARTIN.
